(Cl. D62—4)

To all whom it may concern:

Be it known that I, Cornelius B. Wright, a citizen of the United States, residing at Fort Worth, in the county of Tarrant and State of Texas, have invented a new, original, and ornamental Design for a Portable Air Cooling Device, of which the following is a specification, reference being had to the accompanying drawing, forming part thereof.

In the drawing:

Figure 1 is a perspective view of a portable air cooling device showing my new design;

Figure 2 is a reduced top plan view thereof; and

Figure 3 is a reduced elevational view of the side opposite that shown in Figure 1.

I claim:

The ornamental design for a portable air cooling device, substantially as shown.

CORNELIUS B. WRIGHT.
